UNITED STATES PATENT OFFICE.

WILLIAM B. WILLIAMS, OF READING, PENNSYLVANIA, ASSIGNOR TO ALEX LAUGHLIN, OF SEWICKLEY, PENNSYLVANIA.

RIBBED PIPE.

SPECIFICATION forming part of Letters Patent No. 679,350, dated July 30, 1901.

Application filed April 26, 1900. Serial No. 14,402. (No model.)

To all whom it may concern:

Be it known that I, WILLIAM B. WILLIAMS, a citizen of the United States, residing at Reading, in the county of Berks and State of Pennsylvania, have invented or discovered certain new and useful Improvements in Ribbed Pipes, of which improvements the following is a specification.

It is customary to employ pipes as the supports for billets, &c., in furnaces where it is desired to shift the billet or other article from place to place. As the pipes are maintained at a temperature considerably below that of the furnaces by the water circulating through them, it is evident that the portions of the billets or other articles resting on the pipes will be prevented from being heated to the same temperature as the other portions. Such relatively-unheated portions are known as "black spots," and their extent is proportional to area of contact between the billets and the supporting-pipes. As these black spots tend to prevent an even reduction of the billets, it is desirable to reduce the contacting areas between the billets and pipes to as great an extent as possible and also to reduce as far as practicable the difference in temperatures of the billet-support and the furnace. It has been attempted to attain these desirable ends by securing a narrow metal strip on the pipes by welding or riveting, but without success, as in all cases the strips are burned or torn off.

The object of the present invention is to provide a pipe with a rib or ribs formed integral therewith.

The invention is hereinafter more fully described and claimed.

In the accompanying drawings, forming a part of this specification, Figure 1 is a sectional elevation of a furnace having improved pipe-rails arranged therein. Fig. 2 is a transverse section of the furnace, the plane of section being indicated by the line II II, Fig. 1. Figs. 3, 4, 5, 6, and 7 illustrate different forms of pipe supports.

In the practice of my invention the pipe supports 1 are formed with a rib 2 along one side, or two ribs 2 2^a may be formed on oppo-

site sides of the pipe, so that when the rib 50 on one side is worn down the pipe can be reversed. These ribs may be made of any desired transverse contour, as will be seen by reference to Figs. 3 to 7, inclusive, which illustrate different shapes. These ribbed 55 pipes may be formed in different ways—as, for example, a pipe formed in any of the ways known in the art may be heated to a plastic temperature and then drawn or forced through die or bell or between rolls suitably 60 constructed to compress or squeeze together portions of the pipe to form a solid rib 2, as fully described and shown in application, Serial No. 14,404, filed April 26, 1900. By suitably constructing and proportioning the 65 portions of the bell, dies or rolls which operate on the walls of the pipes to form the rib the opposite walls of the rib may be forced together, forming a solid rib, as shown in Fig. 4.

As described and claimed in applications, 70 Serial Nos. 14,403 and 14,405, filed April 26, 1900, the ribbed pipes may be provided by forming ribs on the pipe-blank and then bending and welding said blank in the usual manner to form the complete pipe. This method 75 is particularly applicable for manufacture of double-ribbed pipes. (Shown in Figs. 5 and 7.)

As shown in Fig. 5 and as described in application Serial No. 14,404, above referred to, 80 two ribs 2 2^a may be formed by suitably bending or swaging opposite sides of a pipe. As set forth in said application, the ribs are formed by forcing the heated pipe through a bell or die having a suitable shaping-matrix 85 or between rolls having a pass of the desired contour. The ribs thus formed on the pipe cannot be torn away without the actual destruction of the pipe itself. As the bearing portion of these ribs can be made narrow, 90 even to a knife-edge, if desired, the contact areas between the pipes and billets will be reduced to a minimum, and such bearing portions being at a relatively considerable distance from the cooling medium circulating 95 through the pipe will be heated nearly to the temperature of the furnace.

It will be understood that the ribbed pipe

while especially adapted for use as supporting-rails in furnaces of all kinds is also adapted for other uses.

I claim herein as my invention—

5 A billet-supporting rail for furnaces, consisting of a wrought-metal pipe having portions of its walls pressed together forming an external solid longitudinal rib integral with

the pipe, such rib forming a wearing-surface, substantially as set forth.

In testimony whereof I have hereunto set my hand.

WILLIAM B. WILLIAMS.
